Paul Scott.
INVENTOR
BY Victor J. Evans
ATTORNEY

UNITED STATES PATENT OFFICE.

PAUL SCOTT, OF WAYNOKA, OKLAHOMA.

BATH BRUSH.

Application filed December 12, 1921. Serial No. 521,746.

To all whom it may concern:

Be it known that I, PAUL SCOTT, a citizen of the United States, residing at Waynoka, in the county of Woods and State of Oklahoma, have invented new and useful Improvements in Bath Brushes, of which the following is a specification.

This invention relates to new and useful improvements in bath brushes and the principal object of the invention is to provide a holder which will grip wash cloths and to which such cloths may be easily applied and as quickly and easily removed.

Another object of the invention is to provide a device of this character which is simple and durable in construction, reliable and efficient in operation and one which can be manufactured and placed upon the market at a minimum cost.

The invention also consists in certain and other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:—

Figure 1 is a perspective view of a cloth holder constructed in accordance with my invention.

Figure 2 is a view showing the device in clamping position ready for use.

My invention consists in a wire element 1 bent to provide a substantially rectangular loop 2 centrally of its ends, and a second wire element 3 bent to provide a rectangular loop 4 centrally of its ends, and further bent to provide a circular loop 5 within said rectangular loop. A handle 6 is designed to receive the wire elements extending from

loop 2 and the wire elements 3 extending from loop 4 are pivotally connected to said handle. The rectangular wire loop 2 is adapted to receive a wash cloth 6 which is folded along dotted lines as shown in Figure 1. The wire element 3 which is bent to form the rectangular loop 4 has a curved portion 7 formed therein near its looped extremity and a ring 8 surrounds the wire elements which is adapted to pass over the curved portion 7 for locking the rectangular loops into engagement. This holder is constructed of non-corrosive and non-rusting metal wire so as to prevent all possibility of infection.

In using the device a cloth is placed upon the loop 2 and folded along the dotted lines as shown in Figure 1 and the rectangular loop 4 is placed upon loop 2 and the ring member 8 is then passed along the wire elements and over the curved portion and thereby locking the wash cloths between the loops.

It is thought from the foregoing description that the advantages and novel features of my invention will be readily apparent.

I desire it to be understood that I may make changes in the construction and in the combination and arrangement of the several parts, provided that such changes fall within the scope of the appended claim.

Having thus described my invention, I claim:

A cloth holder comprising wire elements bent to provide rectangular loops centrally of their ends, one of said wires being further bent to provide a circular loop within one of the rectangular loops, a support holding the free ends of the wire elements, the free ends of said elements being curved at the lower end, a ring member slidably mounted on said wire elements for locking and releasing said loops.

In testimony whereof I affix my signature.

PAUL SCOTT.
